UNITED STATES PATENT OFFICE.

JOHN A. NICHOLAS, OF DENVER, COLORADO.

ATTACHING DEVICE FOR OVERSHOES.

1,175,798.

Specification of Letters Patent. Patented Mar. 14, 1916.

Application filed September 2, 1915. Serial No. 48,684.

To all whom it may concern:

Be it known that I, JOHN A. NICHOLAS, a citizen of the United States, residing at Denver, in the county of Denver and State 5 of Colorado, have invented certain new and useful Improvements in Attaching Devices for Overshoes; and I do declare the following to be a full, clear, and exact description of the invention, such as will enable others 10 skilled in the art to which it appertains to make and use the same.

My invention relates to improvements in devices for retaining overshoes on the shoes of horses and has for its object to provide 15 a simple device of this character which will be very efficient in operation.

Another object of my invention is to provide an attaching means which will take the place of the usual straps and chains.

20 A further object is to provide an attaching means by which the overshoe can easily and quickly be applied to the horse's shoe, and one which will be positive in its action in maintaining the outer shoe on the ordinary shoe of the horse.

25 A still further object of the invention is to provide attaching means which is adjustable to various sizes of horses' shoes.

With these and minor objects in view, 30 my invention consists of the novel features of construction, combination and arrangement of parts which will be hereinafter more particularly described and claimed.

In the accompanying drawings wherein 35 similar reference characters designate corresponding parts throughout the several views: Figure 1 represents a top plan view of an overshoe equipped with my improved attaching device; Fig. 2 is a rear end view 40 thereof; Fig. 3 is an outer side elevation of one of the attaching devices; Fig. 4 is a detail elevation of the outer side of one end of this overshoe showing the groove therein; Fig. 5 is a detail perspective view of the 45 attaching member viewed from its inner face; Fig. 6 is a vertical transverse section taken on the line 6—6 of Fig. 1; Fig. 7 is a detail plan view of a portion of an overshoe showing a modified form of attaching de-

vice for holding said overshoe in position; 50 Fig. 8 is an outer side elevation of this modified form; Fig. 9 is a view similar to Fig. 8 but showing the wear plate removed; Fig. 10 is a transverse section taken on the line 10—10 of Fig. 8; and Fig. 11 illustrates a top plan view of a slightly different 55 form of overshoe having one form of attaching device applied thereto.

In the form of attaching device illustrated in Figs. 1 to 6 inclusive, 1 designates 60 this improved device applied to an overshoe 2 which is shown as applied to the usual form of horseshoe 3 having calks 4 on its rear ends. My improved attaching device is designed for application to any 65 form of overshoe which employs an upright flange rising from a plate which underlies the horseshoe. The aforesaid figures designate this plate as 5 with its integrally formed upright flange as 6 to which the 70 device 1 is secured. This attaching device comprises an attaching plate 7 which is designed with a longitudinal slot 8 adapted to receive therethrough a clamping bolt 9 which extends from a threaded opening 10 75 in the flange 6. Adjacent one end of this longitudinal slot 8 is formed an inwardly projecting stud or lug 11 which is adapted to project into a groove 12 formed in the outer face of the upright flange 6 and is 80 designed to slide therein. From this description, it is evident that by tightening the bolt 9, this attaching plate is securely fastened to said upright flange, and by providing the longitudinal slot this plate can 85 be secured in various adjusted positions relative to said flange. The outer or rear end of this attaching plate 7 has formed integrally with its upper edge a laterally 90 extending arm 13 which is designed to extend inwardly and overlie the upper face of the horseshoe, and the free end of said arm is bent downwardly to form a flange 14 which is adapted to embrace the inner edge of said shoe. The aforesaid groove 95 12 inclines downwardly to a slight extent from its rear toward its front end in order that, when said attaching plate carrying

the arm 13 is moved forwardly, said arm will bind against the upper face of the horseshoe, and when it is in this position the clamping bolt can be tightened, thus 5 securely locking the overshoe to the horse's shoe, the rear calks on said shoe being designed to extend downwardly beyond the rear end of said overshoe as shown in Fig. 3.

10 In the figures from 7 to 10 inclusive, I have shown a slightly modified form of my invention applied to a similarly constructed overshoe. The attaching plate of this form of my invention is designated as 15 and it 15 is provided with a longitudinal slot 16 which opens through the forward edge of said plate. Said plate is provided with an arm 13' having a downturned portion 14' at its free end which act similarly to the 20 arm 13 with its downturned flange 14 and performs the same function that these parts perform. This open slot 16 is designed to receive a pair of headed clamping bolts 17 which project through said slot from 25 threaded openings 18 formed in the upright flange 6' of the horseshoe 2'. The forward one of said openings 18 is positioned in a plane slightly below that of the rearmost opening so as to cause said plate 15 to incline downwardly from its rear end to its 30 forward end. This inclined relation of the openings 18 accomplish a purpose similar to the inclined groove 12 in the preferred form of my invention, causing the arm 13' to bind against the upper edge of the horseshoe when the attaching plate 15 is moved 35 forwardly. A wear plate 19 is interposed between said attaching plate 15 and the headed clamping bolts 17 in order to more 40 positively clamp said plate 15 against the upright flange 6'.

While I have shown the elements best adapted to perform the functions of my invention, it is obvious that various changes 45 in form, proportion, and the minor details of construction may be resorted to within the scope of the appended claims without departing from the spirit or sacrificing any of the principles of the invention. Such 50 departure from the preferred form of construction is illustrated in Fig. 11. In this form, the overshoe 2'' has its upright flange 6'' secured to the inner edge of the plate 5''. The attaching device here shown is 55 similar to the preferred form of the invention, especially the means of adjustably attaching the same with the upright flange of said overshoe. In this case, however, the arm 14'' extends outwardly instead of inwardly as in previous figures, otherwise this 60 form is substantially the same as the preceding.

From the foregoing, it is evident that I have provided a device which can be applied

to several forms of overshoes for securely 65 holding the same to various sizes of horse-shoes.

Having thus described my invention, what I claim is:

1. In combination with an overshoe for 70 horses having plates adapted to underlie the under side of the horseshoe at the ends thereof, each of said plates having a flange rising from one edge thereof; of an overshoe attaching member comprising a flat 75 plate adjustably secured to said flange, a horseshoe engaging member formed on one end of said flat plate, and means for adjustably securing said plate to said flange.

2. In combination with an overshoe for 80 horses having plates adapted to underlie the under side of the horseshoe at the ends thereof, each of said plates having a flange rising from one side edge thereof; of an overshoe attaching member comprising a flat plate adjustably secured to said flange, 85 a laterally extending arm projecting from the upper edge of said flat plate, said arm having its outer end bent downwardly, and means for adjustably securing said flat plate to said flange.

3. In combination with an overshoe for 90 horses having plates adapted to underlie the under side of the horseshoe at the ends thereof, each of said plates having a flange 95 rising from one side edge thereof; of an overshoe attaching member comprising a longitudinally slotted plate adjustably secured to said flange, a horseshoe engaging member formed on one end of said slotted 100 plate, and means for adjustably securing said slotted plate to said flange.

4. In combination with an overshoe for 105 horses having plates adapted to underlie the under side of the horseshoe at the ends thereof, each of said plates having a flange rising from one side edge thereof; of an overshoe attaching member comprising a longitudinally slotted plate adjustably secured to said flange, a horseshoe engaging 110 member formed on one edge of said slotted plate, and a clamping bolt extending through said slot from a threaded opening in said flange.

5. In combination with an overshoe for 115 horses having plates adapted to underlie the under side of a horseshoe at the ends thereof; of a flange rising from one side of each of said plates, each of said flanges being grooved longitudinally and provided 120 with a threaded opening adjacent the end of said groove, a longitudinally slotted plate, a stud projecting from the inner face of said slotted plate into said groove, and a clamping bolt extending through said 125 threaded opening.

6. In combination with an overshoe for 130 horses having plates adapted to underlie

the under side of the horseshoe at the ends thereof; of a flange rising from one side of each of said plates, each of said flanges being provided with a longitudinally extending downwardly inclined groove, and having a threaded opening adjacent the upper end of said groove, a longitudinally slotted plate, a stud projecting from the inner face of said slotted plate into said groove, and a

clamping bolt extending through said slot 10 from said threaded opening.

In testimony whereof I have hereunto set my hand in presence of two subscribing witnesses.

JOHN A. NICHOLAS.
